Wm Wallace White

UNITED STATES PATENT OFFICE.

CHARLES CHRIST, OF LYNDHURST, NEW JERSEY.

TYPE-FORM AND PRINTING-RULE THEREFOR.

1,320,738.

Specification of Letters Patent.

Patented Nov. 4, 1919.

Original application filed August 24, 1918, Serial No. 251,226. Divided and this application filed October 24, 1918. Serial No. 259,529.

To all whom it may concern:

Be it known that I, CHARLES CHRIST, a citizen of the United States of America, residing at 335 Stuyvesant avenue, Lyndhurst, county of Bergen, and State of New Jersey, have invented new and useful Improvements in Type-Forms and Printing-Rules Therefor, of which the following is a specification.

10 My invention relates to type forms and printing rules therefor and is a division of my copending application, Serial No. 251,226, filed August the 24th, 1918.

An object of my invention is the provision of a method of preparing type forms whereby the printing rule is locked against longitudinal as well as vertical movement on the type form.

I will describe one method and two forms 20 of printing rules all embodying my invention, and will then point out the novel features thereof in claims.

In the accompanying drawings, Figure 1 is a fragmentary view showing in perspective one form of printing rule embodying 25 my invention.

Fig. 2 is a fragmentary view showing in perspective one form of type form having applied thereto the printing rule shown in 30 Fig. 1 before the type form is planed down.

Fig. 3 is a view similar to Fig. 2 showing the type form planed down and the printing rule in locked position.

Fig. 4 is a fragmentary perspective view 35 of a modified form of printing rule embodying my invention.

Similar reference characters refer to similar parts in each of the several views.

Referring to the drawings, and particularly to Fig. 1, A designates a printing rule 40 formed from a single length of any suitable material and which comprises a flat bottom wall 10, side walls 11 which are flat for a portion of their width and then merge into 45 longitudinal extending grooves 12. The upper edges 12^a of the grooves 12 overhang the lower edges, as clearly shown in Fig. 1. In the present instance I have shown a printing rule for printing a single line and 50 the top of the printing rule is necessarily formed with a single printing edge 14, however, it is to be understood that I am not restricted to this particular form of printing

edge, as my invention may be used with equal success on a printing rule having a 55 double or triple printing edge.

Referring now to Fig. 2, F designates a printing type form of the usual construction which as here shown comprises a plurality of slugs S formed with complementary projections P spaced apart by channels C. Each channel C extends transversely of the 60 slug and the slugs are adapted to be arranged so that all of the channels are alined to receive a printing rule.

On assembling the printing rule A and type form F, the vertical dimensions of the rule are such that when in the position shown in Fig. 2 the upper edges of the projections P abut the overhanging edges 12^a, while the bottom wall 10 is spaced from the bottom wall of the channel C to permit 65 further downward movement of the rule.

When it is desired to lock the rule A on the type form F, the usual planing down 70 operation is begun by placing the planer on the type form and then hammering it down. During this operation the overhanging edges 12^a are forced downwardly into engagement with the projections P which 75 causes the upper edges of the projections to move toward each other and into their respective grooves 12, forming a longitudinally disposed ridge which interlocks with the groove and thus securely locks the rule 80 within the channel.

The manner in which the projections P are bent to lock the printing rule within the channel C is clearly shown in Fig. 3 of the drawings, and it is to be noted that 90 because of the frictional contact between the walls of the grooves and the projections P, longitudinal movement of the printing rule within the channel is prevented.

From the foregoing description, it will 95 be manifest that I have provided a printing rule which is so constructed that it automatically locks itself within a type form while the form is being planed down and that the locking means is effective to prevent longitudinal as well as vertical movement of the printing rule on the type form.

Referring now to Fig. 4, I have here shown a modified form of printing rule 100 which is generally indicated at A'. This 105 printing rule A' is identical to the rule A

with the exception that the side walls 11 are fluted or corrugated vertically to provide ribs 15. The purpose of the ribs 15 is to provide an additional means for locking the printing rule against longitudinal movement within the channel C of a type form F. It will be obvious that when the printing rule A' is placed downwardly into the channel C, the ribs 15 bite into the confronting sides of the projections P and thus lock the printing rule against longitudinal movement. This locking action is augmented by virtue of the tendency of the projections P to bend inwardly under the action of the overhanging edges 12^a which causes those portions of the projections P adjacent the grooves 12 to move between the ribs 15.

Although I have herein shown and described only one method of preparing type forms and two forms of printing rules, it is to be understood that various changes and modifications may be made herein without departing from the spirit of the invention, and the spirit and scope of the appended claims.

What I claim is:

1. The herein described method of preparing type forms, which consists in assembling slugs and prepared ruling members across the slugs and planing the ruling members for forcing portions of the metal

of the slugs into the ruling members for anchoring the members to the slugs.

2. A metal printing rule for type forms, 35 having grooves therein normally adapted to receive portions of the slugs, and to bend such portions upon application of a planing force directly to the printing rule to anchor the rule to the slugs.

3. A metal printing rule for type forms, having longitudinally extending grooves formed in the sides thereof in such manner that the upper edges of the grooves overhang the lower edges to engage and bend 45 portions of the type forms into locking engagement therewith during the planing operation.

4. In combination, a slug having spaced vertical projections thereon, and a printing rule having means formed on the opposite sides thereof for causing said projections to automatically bend and grip the printing rule when the latter is planed down, whereby said rule is anchored to said slug.

5. In combination, a slug having spaced vertical projections thereon, and a printing rule having means for forcing said projections toward each other to grip the rule when the rule is planed down for anchoring the rule to the slug.

In testimony whereof I have signed my name to this specification.

CHARLES CHRIST.
